UNITED STATES PATENT OFFICE.

CHARLES P. CASE, OF HORSEHEADS, NEW YORK.

REVERSIBLE ROTARY ENGINE.

SPECIFICATION forming part of Letters Patent No. 313,056, dated March 3, 1885.

Application filed May 17, 1884. (No model.)

To all whom it may concern:

Be it known that I, CHARLES P. CASE, of Horseheads, in the county of Chemung and State of New York, have invented certain new and useful Improvements in Reversible Rotary Engines; and I do hereby declare that the following is a full, clear, and exact description of the invention, which will enable others skilled in the art to which it appertains to make and use the same, reference being had to the accompanying drawings, and to the letters of reference marked thereon, which form part of this specification.

The object of my invention is to produce a rotary engine that will economize steam, decrease the friction, to have its parts well balanced to produce a quiet-running engine, and to stop, start, reverse, or cut off steam with the least possible time and labor; also to make a more durable engine of this class than is now in existence.

The nature of my invention consists in first so constructing the pistons that they may be loosely placed upon the shaft, balance themselves, interlock each other, and still more freely to take up any wear upon the cylinder or ends of piston; finally, in other details of construction, which will be fully described, and more particularly pointed out in the claims.

Referring to the drawings, Figure 1 is a cross-section showing a single set of my valves in connection with a reversible engine. Fig. 2 is a similar section, showing two sets of valves in use, whereby the steam-ports on the reversing side of the engine are shortened. Fig. 3 shows a non-reversible engine. Fig. 4 is a perspective view showing the valve-chest, steam-cylinder, and casing all cast in one piece. Fig. 5 is a longitudinal section. Fig. 6 is an end view of pistons with end of piston-shell broken away. Fig. 7 is a section through piston, showing some of the details of construction. Fig. 8 is a view of one of the pistons partly in section with its counterbalance. Fig. 9 is a view of one of the heads that connect the shell of the pistons to the shaft. Fig. 10 is a view of the cut-off and reversing-gear. Fig. 11 is a view of the clutch for operating the exhaust-valve. Fig. 12 is a

view of the slide and extension-piece which connects the cam-wheel and abutment-arms. Fig. 13 shows the extension-piece connected. Fig. 14 is a segmental cut-off and reversing and also throttle valves. Fig. 15 is a segmental filling-piece. Fig. 16 is a perspective view of the rotary valve. Fig. 17 is a view of the device for connecting the operating-levers with the segmental valves. Fig. 18 shows a modification of piston-wheel shell.

The piston and piston-wheel shown in Figs. 1, 2, and 3 are of the ordinary construction.

My piston that I design to use in connection with my engine is shown in Figs. 5, 6, 7, and 8, of which the following is the description.

A is the piston, which extends from the surface of the cylinder to the main shaft, and passing around one side of the shaft C by a reduced portion, is connected to or made integral therewith to a counterbalance, B, the purpose of which is to neutralize the centrifugal force of the piston, thereby reducing friction. A further extension, a, is made projecting from the counter-balance that extends through a slot, k, in the opposite piston. One piston is the duplicate of the other. The faces of the pistons are made detachable to be replaced when worn.

D is the sectional shell in which the pistons are placed, and from which they project a sufficient distance to come in contact with the cylinder. The shell with the heads forms what is called the "piston-wheel." This shell is constructed from a cylinder which is divided longitudinally, a sufficient amount of metal being cut from it in dividing to permit the pistons to easily pass through when the two parts are held together by the heads E, which are on either end of the shell.

Upon the faces of the heads E are projections F, through which are formed guideways G for the pistons. There are also recesses h in the periphery of the heads in line with the guideways for the reception of the extensions i on the end of the pistons. On the outer face of the heads are annular grooves into which are placed packing-rings g, that are set up against the cylinder-cover by light springs to prevent the steam from escaping to the shaft.

C. Packing-strips *i'* are set in the ends of the projections *i* on the pistons. They extend from the outer face of the pistons down into the packing-ring *g* on the heads *E*. These 5 packing-strips are held in place by a dowel-pin, upon which they are free to move between the ends of the pistons and cylinder-covers *H*. From the slot *k* outwardly are bored one or more recesses, *c*, into which are placed 10 pistons *d*.

Through the piston *A* a hole, *f*, is made, into which is placed a double-faced valve, that opens by the pressure of the steam from the side upon which the steam may be acting at 15 the time. This hole by a small passage is in communication with the pistons *d* and the relief-valve. This double valve is only used in reversing-engines; but where a non-reversible engine is used the hole does not extend through 20 but simply from the steam side, connecting with the relief-valve and the pistons *d*.

The above devices are more particularly described and claimed in application filed of even date.

25 From the outer end of recess *c* a passage connects it with a hole, *f*, and recess *m*. In the latter is placed a valve, *m'*.

The devices being duplicated in the other piston, the operation is as follows: Steam entering the ports *l* forces the pistons *d* against the extension *a* of the opposite pistons, thereby keeping them against the cylinder.

To keep a constant unvarying pressure upon the pistons *d*, I provide the relief-valve *m'*, 35 which is similar to a spring safety-valve, and is set to blow off the steam from the recess *c*, when the steam rises above a predetermined pressure, the exit from the valve leading into the exhaust side of the main piston. I also 40 insert a rod, *e*, in holes *e'*, that extend through the pistons and the shaft, (see Figs. 7 and 8,) those in the pistons being counter-bored, leaving a shoulder near its inner end for the coil-springs *e''*. The rod passes through the 45 springs, and has a nut on each end by which the tension of the springs is regulated. After the nuts are screwed upon the rods, the detachable faces of the pistons are then put in place, thus preventing steam from escaping 50 through the holes. The function of the springs and rods connecting the main pistons is to relieve the pressure of the piston upon the cylinder when passing the abutments; by slightly withdrawing them from the cylinder when 55 the steam is off of the main pistons.

Between the shell *D* and pistons *A*, I dovetail a packing-strip, *n*, that extends into and neatly fits the heads *E*, a small space being left between the strips and shell for the steam 60 to set up the said strips against the main pistons. In some cases I form a flange on the shell, either a part of the shell or of a separate piece, upon each side of the pistons, extending them nearly to the ends of the pistons, as 65 shown in Fig. 19. These flanges are also provided with packing-strips.

In Fig. 4 I illustrate the valve-cylinder, steam and exhaust chests, and cylinder, cast in one piece.

L is the steam-pipe—one on each side of the cylinder.

H is the steam-chest with passages *H'* for conducting steam to the end of the valve-cylinder *H''* through the ports *h'*.

I is the outer shell, and J is the cylinder, 75 between which is the exhaust passage-way K, which extends around and forms a steam-covering for the main and valve cylinder, and prevents the condensation of the live steam in the same.

M are the partitions between the steam-chest and exhaust-ways.

The construction shown in Fig. 1 is designed for an engine seldom used for reversing and is of more simple construction and action. The 85 steam-port *o* leading from the valve being made short, the reversing steam port *o'*, having to pass the abutment *N*, is necessarily made longer.

The construction shown in Fig. 2 is designed 90 for a reversible engine, and one in which two sets of valves are used, the steam-ports *o o'* being of an equal length for the forward or backward movement.

In Fig. 3 is shown a non-reversible engine 95 with a single steam-port, *o*. The valves in all of these types of engines are similar, and a description of one will be sufficient for all with one exception.

O is a rotary valve having preferably eight 100 narrow slots or ports, *p*, for the admission of steam from its interior to the cylinder, the steam passing from the steam-chest into the valve through the ports *h'* at each end of the valve. The spindle *p'* of the valve extends 105 out of the chest and is properly geared to bring one of its slotted ports in communication with the steam-ports *o* on each half-revolution of the engine, there being two pistons to the same. Upon the outside of the valve is 110 placed a segmental valve, *Q*, nearly the length of the rotary valve. The segmental valve is made by cutting a slot in each side of a cylinder nearly to its end, leaving the projecting pieces *q q*, that when properly set or moved in 115 relation to the rotary valve will cut off steam or reverse the engine. In the cylindrical end of the segmental valves are two slots, *r*, for the reception of the actuating-piece *r'* that is sleeved upon the shafts *p'*, the sleeve extending outside of the chest and are connected to the levers *r''* for actuating them. The space between the segmental valves is partly filled by a segmental filling-piece, *R*, made the same as the segmental valve, except that there is one 125 slot on its cylindrical end that engages with a stop at the end of the valve-chest to limit its movement. The rotary valve being put in place, the piece *R* is slipped over it, the segmental ends pointing outward. Then the segmental valve is placed on the rotary valve, its 130 segmental ends partly filling the space between

the ends of the filling-piece. The end of the valve Q extends beyond the rotary valve to the depth of the slot r , so that the actuating-piece r' may be connected to the valve. Each 5 of the segmental extensions comes in contact with the cylindrical portions at their ends, and are provided with a packing-piece, s , that is set in their ends and of nearly their width, having springs to set them out.

10 The operation of the valves is as follows: The rotary valve is moving in the direction of the arrows. (See Fig. 1.) The valve Q q q , being open to its full extent, forms the opening 2 to 3, and the rotary valve is so timed that the port I or any of the ports in passing this 15 opening will admit steam for a full stroke of the engine. By moving the valve Q q q to shorten the space 2 to 3, the steam will be cut off in proportion until the valve is brought in 20 contact with the filling-piece p , when the steam is shut off, stopping the engine.

It will be seen that the steam-port for reversing the engine has been kept closed by one of the segments q of the valve in any of 25 the positions mentioned above. To reverse the engine, the segmental valve is still moved in the same direction, carrying with it the filling-pieces p , until they are arrested by the stop when nearly to the steam-port o' . The 30 valve is then open to its full extent, and the engine is running in the opposite direction.

There being two pistons to the engines, necessarily there is a valve at each end of the cylinder. The valves are geared similar to 35 those shown in Fig. 10, or in any well known way, by which the rotary valve is timed with the piston, the cut-off valves being operated by the levers r'' . A connecting-link, F, is placed between the levers, permitting the engine to be operated from either side. The 40 levers may be connected to a governor, making the segmental valve an automatic cut-off valve. On the upper side of the connecting-link T is an extension, t , provided with a slot, 45 into which is fitted the boxes t' that serve as a bearing for the pin u , arm u' , of the clutch U. Within the cylinder are two segmental pieces, v v' , similar to the valve and filling-piece, the piece v being stationary, and v' 50 serving as an exhaust-valve. The cylindrical end of the piece v' enters a recess in the cover of the cylinder, and has upon its periphery a sufficient number of teeth to move it to shut one or the other of the exhaust- 55 ports w . Into these teeth are meshed the teeth of a loose cog-wheel, W, which in turn is meshed with the cog X upon the shaft x .

By the construction above described and shown it will be seen that the steam cannot 60 leak beyond the gearing. Upon the shaft x is keyed one part of the coupling U, while the other part is loosely sleeved thereon, and is held in position by a plate and bolt screwed into the end of the shaft. The two extensions 65 of the coupling are made narrower than the spaces, so that there will be lost motion, the

purpose of which will be described further on. When the levers r' are moved in either direction, the segmental valves are operated as hereinbefore described; also, the same movement operates the exhaust-valve, but owing to the lost motion in the clutch that is operated by the connecting-arm T and the arm u' , the exhaust-valve is not moved until the steam is shut off.

In my application before mentioned, I extend my abutment-roller into the groove of the cam-wheel; but in the present construction the cam-wheel is made smaller, and to connect the groove with the abutment I use 75 the device shown in Figs. 13 and 14.

Y is the guide-plate that is attached to the cylinder-covers, and y is the connecting piece, to one end of which the stud is fixed for the roller, and the other end is secured rigidly to 80 the abutment.

In Fig. 5 I show my adjustable bearing, of which there is one on each end of the cylinder, and is constructed as follows: The extension 4 of the cylinder-cover H is bored out conically upon its inner side, and threaded upon the outside. Within this conical extension, I insert a conical sleeve, 5, that fits the main shaft C, and is made to revolve therein by the feather 8, but permits the conical sleeve to 90 have a longitudinal movement.

6 is a sectional gland which is screwed upon the extension 4, and having inward projecting flanges that enter a groove in the conical sleeve 5. The gland C is made in two parts, 100 so that the flanges will enter the grooves, and the parts are held together by the clamp 7, which consists of a ring divided at one side and provided with flanges and a clamping bolt. Upon the opposite side of the clamping-bolt is placed a dowel-screw, 11, which prevents the clamp from slipping off of the sectional gland. In the outer end of the conical sleeve is placed a set-screw, 9, for the purpose of holding the conical sleeve when once 105 adjusted.

The following is the operation: The clamp is loosened upon the sectional gland, also the set-screw on the conical sleeve. The gland is now turned, which draws in the conical sleeve 115 sufficiently to take up any play between the sleeve and the extension.

The rotary steam and cut-off valves herein described and shown will be made the subject of a separate application.

I claim—

1. In a rotary engine, the combination of the cylinder with the main piston, provided with a counter-weight, and the shell piston-wheel, all as shown, and for the purpose described.

2. In a rotary engine, the combination of the cylinder with the main piston passing around the shafts, and provided with a counter-weight, and the shell-wheel, all substantially as shown and described.

3. In a rotary engine, the combination of

- the cylinder, the shell piston-wheel, with the pistons extending around each side of the shaft, and provided with a counter-weight and slots, and the extensions passing into the 5 slots, all substantially as shown and described.
4. In a rotary engine, the combination, with the main pistons provided with counter-weights and extension, of the balancing-pistons, substantially as shown and described. 40
5. In a rotary engine, the combination of main pistons provided with counter-weights and extensions, the balancing-pistons, and the relief-valves, substantially as shown and described. 45
6. In a rotary engine, the combination of the main pistons having counter-weights with the spring-rod, the shaft, the nuts on the ends of the rod, and the springs, substantially as shown, and for the purpose described. 50
7. In a rotary engine, the combination of the main piston with the two-part shell piston-wheel, and the heads provided with guides upon their inner face, substantially as shown and described. 55
8. In a rotary engine, the combination of the main piston with the two-part shell piston-wheel, the heads, and the main shaft, substantially as shown and described. 60
9. In a rotary engine, the combination of the main pistons, the shell piston-wheel, the heads, and the packing-strips fitting in the heads, having a steam-space between them, and the shell, substantially as shown. 65
10. The combination of the exhaust-valve with the cog-wheels, the clutch having lost motion, and the actuating-lever, substantially as shown and described. 70
11. The combination of the exhaust-valve with the cog-wheels, the clutch, the actuating-lever, and the segmental reversing-valve, substantially as shown. 75
12. The combination of the actuating-levers with the connecting-bar provided with a compensating-bearing for the clutch-arm and the clutch, substantially as shown. 80
13. The combination of the cam-wheel with the abutment, the connecting-link, and its guide, substantially as shown and described. 85
14. The combination of the main shaft with the conical sleeve feathered thereon, the conically-bored cover-extension, and the gland, substantially as shown. 90
15. The combination of the main shaft with the conical sleeve feathered thereon, and provided with a peripheral groove, the two-part gland provided with a flange, the cover-extension, and the clamp, substantially as shown. 95
16. The combination of the main shaft with the conical sleeve feathered thereon, and provided with a peripheral groove and a set-screw, the two-part gland provided with a flange, the cover-extension, the clamp, and the dowel screw, substantially as shown and described. 100

In testimony that I claim the foregoing as my own I affix my signature in presence of two witnesses.
